ABSTRACT

A knit contour unit for a knitting machine in which an input member, drivable by reciprocation of the carriage of the machine, is operatively connected to pattern advancing means through engagement with a drive plate which imparts movement to an input member. The extent of the incremental movement transmitted by the output member to the pattern advancing means is controlled by the selective positioning of the output member on the drive plate. A dial selector is rotatably and depressably mounted in the frame of the unit and automatically effectuates disengagement of the drive plate from the output member when repositioning of the output member is to be effected.

This diagram illustrates an exploded view of a mechanical assembly, likely a clutch or similar mechanism. The components are labeled with numbers:

- 14: A rectangular plate or frame.
- 63: A slot or opening in the frame.
- 64: A central hub or bearing.
- 65: A gear or ring.
- 60: A gear or ring.
- 58: A gear or ring.
- 37: A gear or ring.
- 66: A spring.
- 61: A pin or fastener.
- 72: A slot or opening.
- 67: A pin or fastener.
- 70: A slot or opening.
- 69: A slot or opening.
- 73: A slot or opening.
- 70: A slot or opening.
- 70: A slot or opening.
- 68: A gear or ring.
- 59: A gear or ring.
- 56: A gear or ring.
- 38: A gear or ring.
- 57: A gear or ring.
- 75: A gear or ring.
- 46: A slot or opening.
- 40: A slot or opening.
- 8: A slot or opening.

The diagram shows how these components are assembled, with some parts like 64, 65, 60, 58, 37, 66, 61, 72, 67, 70, 69, 73, 70, 68, 59, 56, 38, 57, 75, 46, and 40 being shown separately from the main assembly.

KNIT CONTOUR UNIT FOR A KNITTING MACHINE

BACKGROUND OF THE INVENTION

This invention relates to knit contour units for knitting machines, particularly home knitting machines. As is well known, in knitting a garment having a contoured configuration — such as the body of a sweater or jumper — when the knitting has proceeded, for example, to the area of the armhole it is necessary to vary the number of stitches per row in order to produce the desired contour. This requires that the operator count the number of rows of stitching already completed and then either estimate the number of increased or decreased stitches per row needed or actually measure the intended wearer to determine such variation. The introduction of patterns from which the variation in the number of stitches per row may be readily obtained was an advance in the art; however, it was nevertheless necessary to count the rows of completed stitches on the garment to establish the variation row by row. In recent years there have been made available to knitting machine operators various types of attachments to assist in keeping track of the point of knitting at all times and to enable the operator to keep accurate count of the number of rows knitted and for retention of a graph of the stitch pattern in an easily observed position. U.S. Pat. No. 2,722,814 granted Nov. 8, 1955 to Anthony P. Ferriazzo may be referred to for details of such an attachment.

More recently, devices generally designated as knit contour units or stitch and row counters have been made available whereby a pattern, representative on a reduced scale of the actual garment to be knitted, is advanced incrementally on a row by row basis by pattern advancing means such as a roller. The pattern is aligned with a stitch scale such that as the carriage of the knitting machine is reciprocated to produce a row of stitches, a ratio regulating mechanism effectuates actuation of the pattern advancing means in response to such reciprocation of the carriage so that the operator may concurrently and easily note visually, without having to count the rows of stitches already completed, the required stitch variation row by row as the knitting proceeds. Japanese Pat. No. 587,607 granted to Silver Seiko discloses a unit of this character. Broadly, units of this type include a rotatable output member which is operatively connectable to the pattern advancing mechanism and to an input member drivable by means actuatable through reciprocation of the carriage. A ratio regulating mechanism enables the operator to vary the ratio of the movement between the input and output members depending upon the particular stitch scale employed. However, one deficiency of such units has been the scoring or frictional wear sustained by intermediate elements in the drive train between the input member and the pattern advancing means. Such scoring or undesirable wear frequently necessitates repair or replacement of the ratio regulating mechanism or of elements thereof. Prior art structures were also somewhat susceptible to being inadvertently jolted out of a selected position to thereby introduce inaccuracies in ratio control.

SUMMARY OF THE INVENTION

In view of the foregoing it is one object of the present

invention to provide a knit contour unit in which operation of the selector dial for establishing the desired ratio control automatically disengages the output element of the ratio control mechanism to thereby reduce wear on elements of such mechanism and increase service life thereof.

Another object of the invention is the provision of a knit contour unit in which certain elements of the ratio selecting train are in permanent engagement whereby accurate and positive ratio selection is assured.

A further object of the invention is the provision of a knit contour unit in which the pattern advancing means is actuated by each reciprocation of the carriage so as to provide an accurate and current stitch and row count.

Other objects and advantages of the invention will become readily apparent upon a reading of the detailed description of the invention.

According to the present invention there is provided a knit contour unit for a knitting machine, comprising a frame, pattern carrying means movably mounted in said frame drivable in response to and in predetermined relationship relative to the movement of the carriage of said machine, said pattern carrying means being adapted to advance a pattern in a row to row direction, a drive plate operably connectable to said pattern carrying means and carried by a shaft mounted rotatably in said frame, scale means for indicating the number of stitches per row of pattern advance, and ratio regulating means for establishing said predetermined relationship between movement of said carriage and movement of said pattern carrying means, said ratio regulating means including a dial member rotatably mounted in said frame and depressable axially with respect to said frame, an input member drivable in response to movement of said carriage and adapted to effect rotation of said drive plate, and an output member rotatable by said drive plate and operatively connected to said pattern carrying means to drive same, said output member being positionable at selected radial locations on said drive plate to establish the desired ratio between the rotation of said input and output members, said dial member carrying means thereon cooperable with racking means connected to said output member whereby depression of said dial member serves to disengage the drive plate from said output member and rotation of said dial member and means carried thereon displaces said racking means and locates said output member at a selected radial location on said drive plate to thereby establish the desired ratio of rotation between said input and output members.

BRIEF DESCRIPTION OF THE DRAWINGS

In order that the invention may be more readily comprehended it will now be described, by way of example, with reference to the accompanying drawings in which:

FIG. 1 is a perspective view of a home knitting machine with a knit contour unit according to the invention attached thereto;

FIG. 2 is an elevational front view of the knit contour unit shown in FIG. 1 with the cover broken away;

FIG. 3 is a side elevational sectional view of the ratio control mechanism of the invention taken along line 2-2 of FIG. 2;

FIG. 4 is a perspective view of the ratio control mechanism and pattern advancing means of the invention;

FIG. 5 is an enlarged view of the circular rack and drive shaft;

FIG. 6 is a bottom plan view of the bell crank and actuating lever arrangement for indexed rotation of the ratchet input wheel partly in section and taken along line 6-6 of FIG. 2; and

FIG. 7 is a cross-sectional view of the roller and tape reel assemblies taken along line 7-7 of FIG. 2.

DETAILED DESCRIPTION OF THE INVENTION

Referring to FIG. 1 of the drawings there is shown a home knitting machine 10 having a needle bed 11 and a carriage 12 adapted to be reciprocated laterally along the needle bed. As is well known, the carriage may be manipulated manually or it may be driven by an electric motor (not shown). Secured to the knitting machine at a convenient location is the knit contour unit 13. Such unit should be so positioned with respect to the carriage of the machine that reciprocation of the carriage along the bed in either direction results in the engagement of the carriage, or an element carried thereby, with an element of the knit contour unit such as actuating lever 14. As will be described hereinafter in greater detail, each such engagement initiates movement of a series or train of elements within the knit contour unit which culminates in the incremental advance of a pattern carrying or advancing means such as roller 15.

The knit contour unit comprises a console or frame 16 preferably molded from an impact resistant plastic material. The housing is provided with a hinged lid or cover 17 to provide access to the roller adjusting knob and other operational elements of the unit. The cover is shown in phantom in FIG. 7 pivoted to a partly open position. Pivotal movement of the lid thus exposes the roller assembly for insertion of a pattern, generally made of paper. The pattern is representative of the garment to be produced by the knitting machine. Such a pattern 18 is shown in phantom. Positioned either directly above or below the point at which the pattern is introduced there is shown a scale 19 which is preferably one of a plurality of scales carried on a continuous tape 20. Reference to FIGS. 2 and 7 of the drawings will reveal that the tape is mounted on a pair of spools or reels 21 which are rotatably supported within the console. To permit registration of any selected scale of the tape with the particular pattern used a pair of reel or scale adjusting knobs 22 are provided. A preferred construction, as may be seen most clearly from FIG. 7, involves the provision of a pair of miter gears 24, 25 carried respectively by the reel shaft 26 and by a stub shaft 27 at the other end of which one of knobs 22 is affixed. The knobs are located within the console so that access is gained thereto by lifting of cover 17.

The knit contour unit is shown as having a dial selector 28 mounted rotatably on the housing so as to be angularly adjustable throughout a predetermined range of rotation. As may be observed, dial selector 28 comprises a handle 29 carried at the upper end of a stem 30 and a pinion 31 carried at the other extremity of the stem. The dial or housing is provided with calibrations 32 adjacent the periphery of the dial selector for indicating the position of the selector in any of a number of selected positions. In order to insure positive locking

of the dial selector in the selected position the console is given a first annular disc-shaped member 33 having a circumferentially downwardly facing toothed or serrated edge surface 34. This member is situated so as to be concentrically arranged about the stem of the dial selector. A second like annular member 35 is affixed to the stem 30 and is normally urged into meshed relationship with member 33 under the influence of spring 36 to be hereinafter described.

10 The dial selector is urged upwardly under the influence of spring 36 so as to effectuate meshing of the said serrated surfaces on members 33, 35. Depression of the selector against the influence of spring 36 causes a disengagement of discs 33, 35 and thus enables the operator to rotate the dial to a different angular position. As will be described hereinafter, the rotation of the dial to a new position serves to establish a different rate of incremental advance for the roller 15.

Reference is made to FIGS. 2 and 3 from which it will be seen that a drive plate or a disc 37 is mounted atop a vertical shaft 38 which is rotatably journaled in the frame of the unit as will be hereinafter described. The upper surface of the drive plate is provided with a facing of a frictional material 39 such as a synthetic rubber or the like for a purpose to be described. The lower surface, preferably the peripheral area thereof, is formed with a plurality of circumferentially spaced detent notches 40 which are dimensioned to receive detent means, described below, in order to retain the drive plate in the rotationally indexed position. The shaft 38 is so mounted within the frame that it is also capable of limited axial movement. Compression spring 36 is positioned about shaft 38 constrained between the lower surface of the drive plate and the bottom plate 41 of the frame. A disengaging lever 42 is positioned within the console and is provided with a flange portion 43 having an aperture therethrough for reception of a pin or shaft member 44 which serves to support the lever in the frame and act as a fulcrum therefor. The lever is pivotably mounted on shaft 44 such that the free end thereof extends over the drive plate preferably the midpoint thereof. The lower surface of the lever is provided with a pin member or protuberance 45 substantially coaxial with shaft 38 which is normally in engagement with the central portion of the drive plate. Spring 36 urges the drive plate into engagement with the protuberance on the lever 42 so as to urge the lever upwardly about its fulcrum and thereby transmit a like biasing force to the dial selector assembly through pinion 31 which is provided with an end section engageable with the lever.

An input member 46, in the form of a ratchet wheel, is positioned immediately below the drive plate and is concentrically arranged with respect thereto and rotatable therewith on shaft 38. A presently preferred embodiment of the invention is to provide the drive plate and ratchet wheel as an integral unit mounted on shaft 38.

Journalized at both ends within the frame is output shaft 47. The shaft is formed with a non-circular cross-section, preferably with a square configuration. Carried slidably on the output shaft is a sleeve member 48. The sleeve member comprises an elongated portion 49 which is formed as a circular rack on its exterior surface and an output wheel or disc portion 50 which is dimensioned to ride in engagement with the upper surface of drive plate 37. The output disc portion is provided with a bore having the configuration of shaft 47

so that sleeve member 48 is not only capable of axial movement along the shaft but is capable of rotational movement with the shaft regardless of its axial position thereon. The circular rack portion of the sleeve member is formed with a bore of sufficient diameter to avoid binding with the shaft during axial movement of the sleeve therealong. Thus, the bore of the circular rack segment of sleeve 48 is given an internal diameter larger than the widest dimension of the shaft. Further, it has been found desirable to form the circular rack and output disc separately and to press-fit the disc onto a reduced end portion of the rack.

One end of output shaft 47 is provided with a pinion 51 which is positioned thereon so as to be cooperable with a pinion 52 on roller shaft 53 to be later described.

As may be observed most clearly from FIG. 3, spring 36 serves to bias drive plate 37 in an upwardly direction into engagement with output disc 50. Thus, in normal operation rotation of the ratchet wheel 46 effects rotation of the drive plate 37 and, because of the facing of frictional material thereon, of output disc 50. This results in rotation of the output shaft 47 and of pinion 51 carried at the end thereof.

As may be seen from FIG. 2, output shaft 47 is journaled at one end thereof in wall 54 formed within the console or frame of the knit contour unit. Output shaft 47 is coupled through pinions 51 and 52 to the pattern advancing roller 15 to transmit rotational drive thereto. Pinion 52 is carried by the roller shaft adjacent the end thereof at a location such that it is in permanent engagement with pinion 51 on the output shaft. Generally, the pinion 52 is larger than pinion 51 so as to effect a step-down in rotational speed. The exact ratio between the pinions is not critical since it depends upon various factors such as space limitations for the drive plate and ratchet wheel and the desired rate of incremental advance for roller 15. Knob 55 is secured to roller shaft 53 at a convenient location so as to afford manual adjustment of roller 15. As with reel adjusted knobs 22, it is necessary to lift the cover 17 to obtain access thereto for manual manipulation.

The circular rack segment of sleeve member 48 and the pinion 51 are so dimensioned and located that these two members are always in engagement; the teeth of the pinion being in meshed relationship with the grooves of the circular rack. Thus, it will be seen that depression of the dial selector 28 against the bias of spring 36 effects a separation of disc-like members 33, 35, the lower end of stem 30 engaging the upper surface of disengaging lever 42 so as to cause the lever to pivot about its fulcrum or shaft 44. As the lever pivots downwardly, pin member or protuberance 45 is caused to press against the drive plate and oppose the force of spring 36 so as to disengage the drive plate from output wheel 50. Rotation of the dial selector 28 and of pinion 31 carried thereby effectuates axial movement of the sleeve member 48 along output shaft 47 due to the co-action between the pinion and circular rack. As the sleeve member moves axially along output shaft 47 it carries the output wheel therewith to a new radial location with respect to drive plate 37. Once the dial selector has been positioned in the desired angular setting and it is released, it is urged back into locked relationship by virtue of the force of spring 36 and the cooperating serrated surfaces on the disc members 33, 35. It will be appreciated that by varying the radial position

of output wheel 50 the ratio of rotational movement between ratchet wheel 46 and the output wheel may be regulated as desired in order to establish the magnitude of the incremental advance of roller 15. Further, the gear ratio between pinions 51 and 52 determines the final speed reduction and establishes the rate of incremental advance by the roller 15. The pattern 18 fed to the roller is thereby caused to advance through its engagement with roller 15.

As may be seen from FIGS. 2, 3 and 6 of the drawings, base plate 41 of the knit contour unit is provided with an upstanding bushing 56, within which shaft 38 is journaled. Carried pivotably by the base of the bushing is a bell crank 57 having a pair of arms 58, 59. Arm 58 is furnished adjacent the end thereof with a cam follower 60 in the form of a roller. The base plate of the console is also provided with a relatively short standard or stand-off 61 which is offset and spaced from bushing 56. Mounted pivotably on standard 61 is an actuating lever 14 which is of sufficient length to extend beyond the face of the console such that when the console is affixed to the knitting machine the protruding portion 63 of the lever is in the path of the reciprocating carriage or striking means carried thereon (not shown). The end of the lever which is carried by standard 61 is provided with a cam head 64 having cam surface 65 engageable by cam follower 60 on the bell crank 57. The lever is formed with a recessed portion that is dimensioned to accept roller 60 in the event of an overrun by the roller of the cam surface. This affords a measure of safety against damage to the bell crank, pawl or other elements in the event the roller is caused to move beyond the extremity of cam surface 65. Spring means 66 is secured between an internal wall of the console and a radially extending lug 67 formed on the cam head opposite cam surface 65. Spring 66 serves to urge the return of the actuating lever to a neutral position when displaced by reciprocation of the carriage as described above.

Arm 59 of the bell crank extends in a substantially radial direction and is provided adjacent the end thereof with an aperture therethrough adapted to receive a pin or rivet member 68 which mounts a pawl 69. The pin or rivet is headed at both ends so as to retain the pawl on arm 59. Pawl 69 is conveniently formed in the configuration of a bell crank, one arm 70 of which is generally arcuate and conforms somewhat to the curvature of the contiguous ratchet wheel. The terminal portion of arm 70 is provided with a tooth element 71 adapted to engage with the teeth of the ratchet wheel to effectuate rotation of such wheel upon clockwise rotation of bell crank 57. The other arm 70' of the pawl extends in the same generally radial direction as does arm 59 of bell crank 57 and is given a notch 72 or other suitable spring retaining means. A spring 73 is anchored at one end thereof to such spring retaining means on the pawl arm 70' and at its other end to suitable retaining means provided on the interior of the console. Spring 73 serves to bias the pawl in a direction such that tooth element 71 is urged into engagement with the adjacent tooth on the ratchet wheel. It will be understood, of course, that pin or rivet member 68 may be rotatable within the aperture in arm 59 or the pawl may be rotatably mounted on the pin or rivet. However, the pawl must be rotatable with respect to arm 59.

It is within the scope of the invention to substitute for the aforementioned ratchet wheel and actuating lever arrangement a motor which is energized selectively by virtue of the generation of electrical impulses upon predetermined movements of the carriage. Drive plate 37 may be thus caused to rotate to transmit incremental rotation to roller 15.

As is well known, mechanisms are readily available in the typewriter field, which include a spring loaded guide tray 74, for receiving a sheet material, such as a pattern 18, so that it may be pressed into engagement with a roller for advance therewith. Similarly, such mechanism is capable of permitting the release of the sheet material whenever desired. Inasmuch as the pattern locking the release mechanism may be any such conventional and heretofore known assembly it is deemed unnecessary to encumber the present specification with a detailed description in this respect.

A spring and ball assembly 75 is shown as being mounted on base plate 41 beneath the drive plate at a location such that the ball, or alternatively a pin member, is biased against the undersurface of the drive plate and urged into one of the detent notches on the drive plate as the plate is rotationally indexed.

From the foregoing it will soon be seen that a knit contour unit has been provided whereby ratio regulating or control means are employed which permit disengagement of the drive plate from the rotatable driven output elements during ratio selection so as to increase the longevity of such elements. Also, the unique arrangement of a pinion and circular rack insures positive and accurate establishment of the desired ratio and minimizes the risk of accidental changes in the selected setting.

Numerous alterations of the structure herein disclosed will suggest themselves to those skilled in the art. However it is to be understood that the present disclosure relates to a preferred embodiment of the invention which is for purposes of illustration only and not to be construed as a limitation of the invention. All such modifications which do not depart from the spirit of the invention are intended to be included within the scope of the appended claims.

Having thus set forth the nature of the invention, what is claimed herein is:

1. A knit contour unit for a knitting machine, comprising a frame, pattern carrying means movably mounted in said frame drivable in response to and in predetermined relationship relative to the movement of the carriage of said machine, said pattern carrying means being adapted to advance a pattern in a row to row direction, a drive plate operably connectable to said pattern carrying means and carried by a shaft mounted rotatably in said frame, scale means for indicating the number of stitches per row of pattern advance, and ratio regulating means for establishing said predetermined relationship between movement of said carriage and movement of said pattern carrying means, said ratio regulating means including a dial member rotatably mounted in said frame and depressable axially with respect to said frame, an input member drivable in response to movement of said carriage and adapted to effect rotation of said drive plate, and an output member rotatable by said drive plate and operatively connected to said pattern carrying means to drive same, said output member being positionable at selected radial locations on said drive plate to establish

the desired ratio between the rotation of said input and output members, said dial member carrying means thereon cooperable with racking means connected to said output member whereby depression of said dial member serves to disengage the drive plate from said output member and rotation of said dial member and means carried thereon displaces said racking means and locates said output member at a selected radial location on said drive plate to thereby establish the desired ratio of rotation between said input and output members.

2. A knit contour unit according to claim 1, wherein said pattern carrying means is a roller mounted on a shaft which is in turn rotatably carried by the frame of the machine, said output member being a wheel integral with said racking means, said wheel and racking means comprising a sleeve mounted slidably on an output shaft and rotatable therewith, means being carried by said roller-mounting shaft and output shaft cooperable to effect driving of said roller-mounting shaft by said output shaft.

3. A knit contour unit according to claim 1, wherein said dial member surmounts a stem to the other end of which a pinion is secured, said racking means being a circular rack integral with said output member and cooperable with said pinion, said rack and pinion being dimensioned so as to maintain engagement therebetween in all movable positions of said dial member.

4. A knit contour unit according to claim 3, wherein a lever member is pivotably mounted within the frame thereof positioned above said drive plate, the lower surface of said lever being provided with a protuberance engageable with said drive plate at approximately the mid-point thereof, said drive plate being spring-biased upwardly into frictional engagement with said output member whereby depression of said dial member effectuates pivotal movement of said lever and disengagement of said drive plate from said output member.

5. A knit contour unit according to claim 4, wherein said input member comprises a ratchet wheel secured to the said shaft which carries said drive plate.

6. A knit contour unit according to claim 5, wherein a bell crank is pivotably mounted on the base plate of the frame beneath said ratchet wheel, one arm of said bell crank being actuatable by a lever pivotably mounted on said base plate engageable upon reciprocation of said carriage by means thereon, the other arm of said bell crank being provided with a pawl which is adapted to index said ratchet wheel upon actuation of said one arm whereby reciprocation of said carriage effectuates movement of said lever with consequent indexed rotation of said ratchet wheel.

7. A knit contour unit according to claim 6, wherein the undersurface of said drive plate is provided with a plurality of circumferentially spaced detent notches, a spring loaded detent assembly being mounted on said frame beneath said drive plate and positioned so that the spring of said detent assembly urges detent means into one of said notches each time said ratchet wheel is rotated whereby said drive plate is rotationally indexed and maintained in the position to which it is rotated.

8. A knit contour unit according to claim 3, wherein a first annular member having a circumferential downwardly facing serrated edge surface is secured to an inner surface of said frame, said annular member being concentrically arranged about the stem of said dial

member, said stem being provided with a second concentric like annular member the serrated edge surface of which is adapted to mesh with the serrated surface of said first annular member to lock the dial member

in a selected setting, said annular members being normally urged into meshed relationship and separable by depression of said dial member.
